UNITED STATES PATENT OFFICE.

JACOB MANDREY, OF NEW YORK, N. Y.

CLOTHES-LINE GRIP.

SPECIFICATION forming part of Letters Patent No. 769,620, dated September 6, 1904.

Application filed May 21, 1903. Serial No. 158,135. (No model.)

To all whom it may concern:

Be it known that I, JACOB MANDREY, a citizen of the United States, and a resident of the city of New York, borough of the Bronx, in the county and State of New York, have invented a new and Improved Clothes-Line Grip, of which the following is a full, clear, and exact description.

My invention relates to an improved form of gripping or holding device especially adapted for the use of holding ropes, clothes-lines, cables, belts, wires, or the like to permit the same to be readily released or put in a gripping position, the object being to provide a grip of simple and inexpensive character so arranged as to firmly hold the line from slipping without danger of cutting into the strands and to provide a means whereby the gripping-face of the holding device may present selective frictional holding-surfaces for articles of varying thickness to correspond with the particular physical properties or conditions of the article to be gripped or held and whereby the article so gripped or held may be quickly and readily released without abrading or destroying its tensile value.

As an example of the adaptation of my gripping or holding device I will describe it as applied as a clothes-line grip, as illustrated in the accompanying drawings, of which—

Figure 1 is a perspective view of a clothes-line provided with my improved gripping device, and Figs. 2 and 3 are sectional views of the gripping parts in different positions.

Referring to the drawings, 1 designates a hollow block or block-shell, the inner wall 2 of which forms a means for retaining and bringing the article to be held in a gripping position by the coaction of the eccentric grip 3, suitably pivoted or mounted in the block-shell and having ratchet-shaped teeth or holding devices 4 arranged upon its periphery in such selective form as to present to articles of various thickness a particular and preferable character of frictional resistance in order that the utility of the article so gripped will not be weakened or deteriorated in value.

The eccentric grip 3 is provided with a device 5, extending outside of the block-shell 1,

whereby the eccentric grip may be actuated 50 to bite or release the article in juxtaposition to the device 2 by moving it backward or forward.

In the operation the end of the rope, line, or other article is passed between the eccentric gripping-plate 3 and the device or wall of the block 2, while the eccentric gripping device is in such a position as to allow the same to pass therethrough readily without material resistance and drawn tightly to take 60 up the slack. The eccentric gripping device is then moved forward by means of the actuating device 5 until it grips or bites the article between the selective holding projections at the periphery of the eccentric gripping device and the wall of the block 2. The article so gripped will then be normally held by the gripping device so long as any tension on the article is exerted in a direction having a tendency to move the gripping-eccentric toward 70 the point of the shortest distance between the periphery and the pivot of the eccentric. The article so gripped may be readily released by moving the eccentric in the direction of its longest distance between the pivot and its 75 periphery by means of the device or finger-piece 5, whereby the distance between the periphery of the eccentric with the gripping devices thereon and the wall of the block-shell 2 is increased to such a degree that the 80 article is disengaged, when it may be quickly and readily removed or withdrawn.

The distinguishing feature of my invention lies in the fact that in combination with or upon the periphery of the eccentric gripping device 1 provide frictional or biting devices of a character which when presented to articles of varying thickness between the eccentric gripping device 3 and the wall of the block-shell 2 will engage and hold the same 85 without injuring the article gripped or deteriorating its tensile value by breaking, cutting, or abrading the surface or strands of the same. The form of varying biting devices which I prefer to employ in connection 90 with my invention as applied to a rope or cable grip is of serrated character, the serrations or teeth being so arranged that a con-

siderable number of small serrated projections will engage a rope or cable of small diameter, the said small serrations being situated on that portion of the periphery of the eccentric located at the farthest distance from the pivot thereof, the succeeding or following serrations around the periphery toward the point of shortest distance from the pivot being gradually increased in depth and distance from each other, the advantage of this variation in the character of the serration or biting devices on the periphery of the eccentric or in combination therewith being that the small serrations will pinch and bite a rope of small diameter, while a biting device of the same size would have a tendency to abrade or scrape the surface of a rope of large diameter. The increasing depth of the various serrations causes the gripping device to take a deeper bite in the ropes of larger diameter, and the movement of the eccentric forward or backward in enlarging or lessening the space between the periphery of the eccentric 3 and the wall of the block-shell 2 to permit of the passage of ropes of varying diameter automatically brings the teeth or serrations of selective gripping character to the particular rope employed opposite the wall of the block-shell 2, whereby the advantage of the gripping device of selective frictional character is utilized in coaction with the wall of the block-shell 2 for the purpose of biting and holding the said rope without injuring or abrading its surface or deteriorating its value or strength.

35 It will be noted that the gripping or holding device consisting of the combination of parts hereinbefore specified is provided with a means for suitably attaching or suspending the same in any convenient manner as desired, such as a ring, as shown in the accompanying drawings, located at or near the point at which the material is gripped and held between the biting devices 4 at or on the periphery of the eccentric 3 and the wall of the block-shell 2.

40 Having now described my invention, what

I claim as new, and desire to secure by Letters Patent, is—

1. A gripping or holding device consisting of a block-shell having a gripping element pivoted therein, the gripping element being provided with biting devices graduated in size, the ends of the smaller biting devices being disposed at a greater distance from the pivot than the ends of the larger biting devices. 55

2. A gripping or holding device consisting of a block-shell having an eccentric therein, the eccentric being provided with biting devices graduated in size, the smaller biting devices being disposed at a greater distance from the pivot than the larger biting devices. 60

3. A gripping or holding device consisting of a block-shell having an eccentric pivoted therein, the eccentric being provided at its periphery with teeth graduated in size, the distance of the teeth from the pivot being inversely proportional to their size. 65

4. A gripping or holding device consisting of a block-shell having an eccentric pivoted therein, the eccentric being provided with biting devices graduated in size, the distance of the biting devices from the pivot being inversely proportional to their size, and means for engaging and releasing the same with and from the article desired. 70

5. A gripping or holding device consisting of a block-shell having an eccentric pivoted therein, the eccentric being provided with biting devices graduated in size, the distance of the biting devices from the pivot being inversely proportional to their size, and means whereby the gripping devices may be suitably attached or suspended. 80

In testimony whereof I have signed my name to this specification in the presence of two subscribing witnesses. 85

JACOB MANDREY.
